ELECTRON DISCHARGE DEVICE CIRCUITS

John E. Young, Oaklyn, N. J., assignor to Radio Corporation of America, a corporation of Delaware

Application December 30, 1941, Serial No. 424,878

3 Claims. (Cl. 315—38)

This invention relates to improvements in electron discharge device circuits. Although the invention is hereinafter described with particular reference to a transmitter it should be understood that the novel features thereof are not limited to transmitting equipment, and have application to receivers as well as to industrial equipment which may have no relation to communication systems.

One feature of the present invention comprises a push-pull electron discharge device system having a pair of vacuum tubes whose grids are supplied with bias through individual resistors. Broadly, this feature applies to any arrangement of vacuum tubes which contribute their output energies to a common utilization circuit, or, putting it another way, the feature is applicable to vacuum tubes whose inputs are connected in parallel as well as to vacuum tubes whose inputs are connected in push-pull.

Another feature of the present invention comprises the use of a high reactance transformer in the filament circuit of a vacuum tube for the purpose of limiting the starting current.

Still another feature resides in the use of one or more voltage limiter tubes of the gaseous type across the primary winding of a transformer for protecting a vacuum tube from surges of power resulting from the transfer of energy from the secondary circuit to the primary circuit in the event of failure in the normal operation of the equipment associated with the primary winding.

A further feature lies in the use of a novel tuning means for an oscillatory circuit associated with a vacuum tube system. This novel tuning means has particular application to electron discharge devices of the type employing an elongated anode or anode socket, and includes the use of a metallic surface spaced from the elongated anode to form a capacity therewith, which surface is movable in a direction over the length of the anode socket to vary the capacity therebetween.

A more detailed description of the invention follows in conjunction with the drawing, wherein:

Fig. 1 illustrates, by way of example only, a frequency modulation transmitter embodying the features of the invention; and

Fig. 2 illustrates the novel tuning means of the invention which can be used as an alternative for the plate-tank tuning circuit of Fig. 1.

Referring to Fig. 1 in more detail, there is shown a frequency modulation transmitter comprising a pair of push-pull connected power amplifier vacuum tubes 1 and 2, each of which has

an anode, a cathode and a grid. The grids are shown connected together through a tuned input circuit 3 comprising leads 4 and 5 and by-pass condenser 6. A pair of series arranged vernier tuning condensers 7, 7 are connected across the conductors 4 and 5 at a suitable location spaced from the by-pass condenser 6. The grids of the vacuum tubes 1 and 2 are individually supplied with suitable bias potentials through resistors 8, 8 which may, if desired, be adjustable to compensate for any difference in the characteristics of the vacuum tubes. In practice, it is preferred that the vacuum tubes 1 and 2 be identical in type, in which case resistors 8, 8 will be of the same value. By supplying the grids with individual biases as shown, the effect of a slight difference in the dynamic characteristics of the vacuum tube is prevented from seriously affecting the operation of the tubes. The frequency modulated input waves are applied to the tuned input circuit 3 by means of line 9 whose conductors are slidably connected to the leads 4 and 5. It should be noted that connection of the circuit 9 to the input tuned circuit occurs at points between the condensers 6 and 7, 7.

The filaments of the vacuum tubes are shown connected together and to ground, from a radio frequency standpoint, by means of condensers 10, and are individually supplied with heating energy from a two-phase supply through high reactance type transformers 11, 11. Although the filaments are shown connected to individual transformers, it should be understood from a practical standpoint that, if desired, these filaments may be connected together to the secondary winding of a single high reactance type transformer. The use of a two-phase supply with individual transformers for the different filaments has the advantage of minimizing the effect of the filament heating current introducing amplitude modulation of the output of the transmitter. The purpose of the high reactance transformer 11 is to limit the surge of current through the filament when the filaments are first energized. The transformers are so designed that they have sufficient reactance to prevent the initial in-rush current from exceeding twice the normal running current of the filament, thereby assuring freedom from mechanical strains or breakage in the filament structure. These high reactance transformers comprise, in effect, a pair of loosely coupled windings so designed that a certain amount of leakage between the windings is deliberately introduced. From a practical standpoint, the primary and secondary windings of each trans-

former 11 can have a common core with windings either coiled around different portions of the core, or else coiled around the same portion of the core but suitably spaced to give the desired result.

The anodes of the push-pull power amplifier tubes 1, 2 are connected together through a tuned circuit 12 whose tuning can be varied by means of a slider 13 bridged across the conductors of the tuned circuit. Output energy which may be supplied to a suitable antenna, not shown, is derived from the pick-up loop 14 located in the field of the tuned circuit 12. This pick-up loop is U-shaped in form and has one leg thereof coupled to one conductor of the output tuned circuit and the other leg thereof coupled to the other conductor of the output tuned circuit. One terminal of the loop is connected to ground through a variable condenser 15, while the other terminal is connected to the load circuit through a variable condenser 16. By varying the angular position of the loop, there is obtained a variation in the magnitude of the output induced in the loop from the tank circuit 12. A positive polarizing potential is supplied to the anodes by means of lead 17 which is connected in series with a choke and resistor parallel combination 19. The choke coil serves to block radio frequency energy from the power supply while the resistor serves to damp parasitic oscillations.

A portion of the output energy is taken off through condenser 20 and rectified in 21, then amplified in 22 to feed back to the plate tuned circuit 12 through transformer 18 energy to reduce the magnitude of the amplitude modulation noise. In effect, the circuit 20, 21, 22 and 18 may be considered a feed back amplifier which picks up a portion of the carrier output of the transmitter, rectifies it, and then amplifies the resulting amplitude modulation signal caused by hum and noise, to thereby modulate the power amplifier stage. The phase relations and gain of this feed back amplifier are such that amplitude modulated noise of the transmitter is reduced by a considerable amount. The feed back amplifier serves not only to reduce the noise but also to reduce the undesired amplitude modulations present as a result of the signal. To protect the vacuum tubes in apparatus 22 from surges in the power amplifier, due to some failure in either vacuum tubes 1 and 2 or the circuits associated with these tubes causing a current in the secondary winding of transformer 18 to induce a high voltage in the primary winding of this transformer, there are provided a pair of gaseous voltage limiter tubes 23, 23 arranged in series relation and across the primary winding of transformer 18, as shown. Although two voltage limiters are shown in series, it should be understood that, if desired, they may be replaced by a single voltage limiter tube of the proper rating.

In one embodiment of the system of Fig. 1 constructed and successfully reduced to practice, the system functioned to amplify a frequency modulated input in the range of from 42 to 50 megacycles. The vacuum tubes 1 and 2 were RCA 889R type tubes, the resistors 8, 8 were each composed of two resistors in series of 1600 ohms each, the condenser 6 had a value of approximately 200 mmf., the amplifier 21 was an RCA 6ZY5G, while the amplifier 22 consisted of three stages comprising a first audio stage having an RCA 6J7 tube, the second audio stage comprising an RCA 807 tube, and a modulator stage comprising four RCA 845 tubes in parallel.

Fig. 2 shows an alternative form of tuning arrangement for the plate-tank circuit 12 which can be used instead of the bridging slider 13 of Fig. 1. The tuning system of Fig. 2 is applicable primarily to vacuum tubes having an elongated metallic anode or metallic anode circuit which is usually the case in high power amplifiers where fluid cooling of the anode is employed. The power amplifiers 1 and 2 are shown in Fig. 2 diagrammatically only, the elongated anodes A, A being designated since these are the only elements of the tubes necessary for an understanding of the novel tuning feature to be described. The elements A, A may either be the elongated anodes or metallic shells into which the anodes are inserted and directly connected. These shells may serve for mounting the vacuum tubes. Variation in tuning is obtained by means of sliding metallic block 24 shaped in the form of a triangle 10 to fit in the space between the two jackets A, A so as to be movable vertically up or down in the space between them. The metallic block has arcuate shaped grooves adjacent both jackets A, A of the vacuum tubes 1 and 2 and is capacitively 20 coupled thereto. This block is movable in a vertical direction by means of a threaded guide or lead screw 25 in turn linked to a suitable dial or handle 26. It will be apparent that as the metallic surface 24 is moved in a downward direction, that less and less of the surface of the block becomes adjacent to the anode shells A, A, as a consequence of which there will be less and less capacity between the anodes. By the same token, as the metallic surface 24 moves upward, 30 more and more of its surface will become adjacent the anode shells A, A, as a result of which there will be more and more capacity between the anodes of the device. This movement of the block 24, with its consequent change in capacity 35 between the anodes, cause a change in the capacity and hence a change in the tuning of the output tank circuit 12. In the particular vacuum tubes 1 and 2 used in the construction successfully tried out in practice and referred to above, 40 the anodes had metallic fins connected to them to aid in heat radiation, and these fins were inserted into the anode sockets A, A which consisted merely of a metallic sheet surrounding the 45 edges of the fins and directly joined thereto.

What is claimed is:

1. In combination, a pair of electron discharge devices having their anodes mounted in vertically arranged cylindrical metallic sockets, a tuned circuit connected to said anodes, a tuning element capacitively coupled to both sockets, and control means for moving said tuning element vertically to bring more or less surface adjacent said sockets, said tuning element having arcuate grooves adjacent and enclosing at least a portion of said cylindrical metallic sockets, said control means comprising a lead screw threadedly engaging said tuning element.
2. In combination, a pair of electron discharge devices having their anodes mounted in vertically arranged cylindrical metallic sockets, a tuned circuit connected to said anodes, and an elongated metallic tuning element capacitively coupled to both sockets, said tuning element having arcuate grooves adjacent and enclosing at least a portion of said cylindrical metallic sockets and which grooves terminate in a vertical line midway between said sockets, and means for moving said tuning element vertically to bring more or less 60 of its surface adjacent said sockets.

3. In combination, a pair of electron discharge devices having their anodes mounted in parallelly arranged cylindrical metallic sockets, a tuned circuit connected to said anodes, and an elongated metallic tuning element capacitively coupled to both sockets, said tuning element having arcuate grooves adjacent and enclosing at least

a portion of said cylindrical metallic sockets and which grooves terminate in a line midway between and parallel to said sockets, and means for moving said tuning element in a direction along said line to bring more or less of its surface adjacent said sockets.
